SCUM SKIMMER

Arthur Wormser, Lawrence A. McKinney, Irvin W. Machacek, and Jack E. Haston, Tucson, Ariz., assignors to Infilco Incorporated, Tucson, Ariz., a corporation of Delaware

Application December 24, 1954, Serial No. 477,492

8 Claims. (Cl. 210—523)

This invention relates to a device for removing floatable matter from liquids, such as the skimming of froth from the surface of liquid clarifiers.

An object of the invention is to provide an improved skimming device for use in treating tanks, such as settling basins, flotation units, or other liquid treatment apparatus.

Another object of this invention is to provide an improved skimming device wherein the skimmer blade conforms to the face of the ramp of a scum trough sufficiently to prevent the floating material from forming a wedge on the ramp and the blade from sliding over the material.

Another object of the invention is to provide a skimming device wherein a maximum amount of floating material with a minimum amount of liquid is carried up the ramp of a scum trough by the skimmer blade.

Other objects will be apparent from the description and the claims which follow.

The skimming device of the present invention is adapted for use in liquid treating apparatus of all types in which it is desired to remove floating material. The skimmer will be described for purposes of illustration, but not of limitation, as used in connection with a circular clarifier in which flotation is employed to promote the clarification of the liquid being treated. However, it will be understood that the basin need not be round, but may have a different configuration.

In the treatment of liquid, and particularly in the treatment of waste liquids by flotation, the impurities in the liquid rise to the surface of the liquid in the form of a scum or froth, being commonly termed "float." This float must be removed from the surface of the liquid and discharged to waste, or further treated to recover any valuable constituents.

Various methods have been used for removing the froth or float from the surface of the liquid. For example, skimmers used theretofore usually comprise a vertical rotatable shaft in the center of the tank, a skimmer arm attached thereto, and a scum scraper or blade fixed to the skimmer arm. As the skimmer arm rotates about the tank center, the blade pushes scum toward a scum trough, which usually extends radially inwardly from the outer wall of the tank. The upper edge of the scum trough is ordinarily placed above the surface of the liquid so that the liquid cannot drain into the trough. Upon the forward edge of the trough, that is, the direction from which the skimmer arm approaches, is placed a ramp sloping from the upper edge of the trough down below the surface of the liquid. When the blade reaches the ramp, it will push the scum up along the ramp and into the scum trough, from which it can be removed by any suitable means. In order to make the blade conform to the face of the ramp, the blade frequently has been made of flexible material, with the result that the blade had a tendency of sliding over float on the ramp rather than pushing it into the scum trough.

The present invention provides a scum skimmer which efficiently removes the scum from the liquid without removing a large volume of the liquid itself. Briefly, the

2

invention comprises a skimmer blade that is mounted on a rotatable skimmer arm in a manner such that it is free to move, within predetermined limits, with respect to the skimmer arm and therefore to the surface of the ramp, so that the lower edge of the blade progressively and freely adjusts itself to the surface of the ramp as it rises thereon until it is in contact therewith for its full length. The blade, therefore, may be made of rather stiff material so that it pushes the float up the ramp to the trough, and does not ride over it.

The invention will be more readily understood by reference to the drawings, which form a part hereof and wherein:

Figure 1 is a partial plan view, partly in section, of a clarifier utilizing a skimmer according to the invention;

Figure 2 is a vertical section of the scum trough on line 2—2 of Figure 1;

Figure 3 is a vertical sectional view, on an enlarged scale, on line 3—3 of Figure 1; and

Figure 4 is a vertical sectional view, on an enlarged scale, on line 4—4 of Figure 1.

As shown in Figure 1, a clarifier 10 has a circular upstanding wall 11 to which is rigidly fixed, as by welding, a scum trough 12 in such manner that the wall 11 forms one end wall of the trough 12. One side wall of the trough 12 is formed by a vertical plate 13 that projects radially inwardly from the wall 11. The other end wall of the trough 12 is formed by a plate 14, made in the shape of an arc of a circle, which has an extension piece 15 that serves as a baffle plate. The other side wall of the trough 12 is formed, as best seen in Figure 2, by the plate sections 16 and 17 and the ramp 18. The upper edge 20 of the ramp 18 also extends radially of the clarifier 10. The lower or leading edge 21 of the ramp 18 is parallel to the upper edge 20. The bottom 22 of the trough 12 slopes downwardly from the end wall 14 to the wall 11 of clarifier 10 in order that float that collects in the trough moves readily out of it through the outlet 23 in the wall 11.

A drive shaft 25 is located in the center of the clarifier 10 and is driven by any suitable means, such as a motor-reducer, not shown. Rigidly connected to the drive shaft 25 is a bracket 26 to which is fixed a skimmer arm 27. As best seen in Figure 3, a bar 28 is pivotally connected to skimmer arm 27. The pivot connection generally indicated at 30 includes a hub 31 which is fixed to the bar 28 and into which is pressed a bushing 32. A hollow spacer 33 is inserted into the bushing so that it projects out of the bushing 32 at both ends. Thrust washers 34 are placed on the projections of spacer 33. A pivot pin or bolt 35 has a retaining washer 36 placed on it, and the bolt 35 is passed through the spacer 33 and a hole in the skimmer arm 27. A nut 37 and a lock washer 38 complete the pivot connection.

Fixed to the bar 28 on opposite ends thereof are brackets 41 to which are pivotally connected links 42 by any suitable means, such as pins 43. Each link 42 is provided with an extension 44 which projects beneath the skimmer arm 27 so that the end 45 of the extension provides a stop that limits the lower position of the links 42.

Extension 44 is adjustably fixed against link 42 by means of a pivot connection 46 and a bolt 47 that is fixed to extension 44 and passes through a slotted hole 48 in link 42. After the proper adjustment of the extension 44 is made with respect to the link 42, a nut is tightened on bolt 47.

Rigidly connected to the links 42 is a skimmer blade 50 in such manner that the blade 50 extends on a radius of the clarifier 10. While the skimmer blade itself can be used for skimming, we prefer to provide a squeegee 51, fixed to the skimmer blade 50 by means of a keeper 52. The squeegee 51 extends below the skimmer blade and

also projects laterally of the skimmer blade at both ends. The portion of the squeegee 51 that does not project laterally of the skimmer blade 50 is made of relatively stiff material; but the portion of the squeegee 51 that does extend laterally of the skimmer blade 50 is made of relatively flexible material, so that it will readily yield when it comes in contact with the extension piece 15 of end wall 14 and the wall 11 of clarifier 10.

While the side wall 13 of trough 12, the upper edge 20 of the ramp 18, and the blade 50 are shown for purposes of exemplification as extending radially of the clarifier, all three members may be made tangent to a circle concentric with the clarifier 10.

Guides 55 are placed across the trough from the upper edge 20 of the ramp 18 to the top of the side 13 so that the blade is carried across the trough without dropping into it. In order to prevent splashing as the skimmer blade 50 is returned down into the liquid, ramp members 56 are fixed to the top of the side wall 13 leading down into the liquid.

The operation of the skimmer will be readily understood. As the skimmer arm 27 and blade 50 are rotated in the clarifier 10, and before the squeegee 51 reaches the lower edge 21 of the ramp 18, the blade 50 is hanging down in the lowermost position permitted by the ends 45. Preferably the extensions 44 are adjusted so that their ends 45 are in contact with the underside of the skimmer arm when the lower edge of the squeegee 51 is in the same horizontal plane as the lower edge 21 of the ramp 18. As the blade 50 is rotated, the outer edge of the squeegee 51 is in contact with the wall 11, and the float on the surface of the liquid is pushed forward in the direction of the arrow in Figure 1 toward the ramp 18 of the scum trough 12. As the blade approaches the ramp 18, it also contacts the extension piece 15 of the end wall 14, thereby enclosing the float in front of the blade between the wall 11, the extension piece 15, the blade 50 and the ramp 18. The first contact between the squeegee 51 and the lower edge 21 of the ramp 18 occurs at the innermost point of the edge 21. The squeegee 51 moves progressively onto the ramp 18, and simultaneously the weight on the bar 28 is relieved between the inner end of the bar and the pivot connection 30. The end of the extension 44 of the inner link 42 remains in contact with the underside of the skimmer arm 27 as the bar 28 rotates about the pivot 30 in counterclockwise direction, looking in the direction of the arrow in Figure 1, while the end 45 of the extension 44 of the outer link 42 moves down away from the skimmer arm 27. As a result of this action and because the pivot connection 30 is spaced closer to the inner link 42 than to the outer link 42, the squeegee 51 drops at its outer end while the inner end continues to rise along the ramp 18. The inner edge of squeegee 51 will be flexed due to the resulting sidewise movement. However, because of the extension of its outer edge the squeegee will remain in contact with the wall 11 and the extension piece 15. During this initial stage of travel of the skimmer up the ramp 18, the only point on the lower edge of the squeegee 51 that is in contact with the ramp 18 is the innermost end, while that portion of the squeegee 51 between the innermost end and the point just passing over edge 21 rises above the face of the ramp 18 so as to form therewith a small triangular gap. This gap becomes first progressively larger and then smaller as the point of contact of the innermost end of the squeegee rises on the face of the ramp 18. When the innermost end of the squeegee 51 reaches a certain point up on the face of the ramp 18, line contact is established and the triangular gap no longer exists. The position of the blade on the ramp when line contact is established is a function (a) of the ratio of the distances between the pivot 30 and the inner and outer link 42, respectively; (b) of the ratio of the distances from the blade 50 and from the stops 45 to a vertical plane through pivots 43; and (c) of the location of the links 42 with respect to the ends of the blade 50.

After the squeegee 51 has come in line contact with ramp 18 and while it continues to rise higher on the ramp, the end 45 of extension 44 of the inner link 42 loses contact with the skimmer arm 27. Simultaneously, the bar 28 rotates in a clockwise direction and the line contact between the squeegee 51 and the ramp increases until finally the squeegee is in contact with the ramp over its entire length. As soon as the full length of the squeegee is in contact with the ramp, the float in front of the blade 50 is trapped and is prevented from escaping rearwardly or sidewise as it is pushed up the ramp. As the squeegee approaches the upper edge 20 of the ramp 18, it gradually becomes more nearly parallel to the edge 20, thereby approaching a level plane. At the instant the squeegee 51 is about to pass over the upper edge 20 of the ramp 18, it is in contact with, and parallel to, the edge 20 over its entire length. The squeegee 51 then crosses the scum trough 12, resting on the guide members 55, moves over the side wall 13, and is lowered back into the liquid down the ramp members 56.

This action of the skimmer mechanism involves a minimum amount of flexing of the squeegee 51, thereby allowing the squeegee to be made of rather stiff material. Such a stiff squeegee is capable of moving much larger amounts of float up the ramp 18 than the usual flexible squeegees. However, the lateral edges of the squeegee 51 which extend beyond the blade 50 should be of soft, pliable material so that the lateral movement of the blade 50 due to the relative motion between the blade 50 and the skimmer arm 27 will not be restricted.

Many modifications of the invention shown for exemplification and illustration could be made without departing from the scope and spirit of the invention. Thus, while one trough and skimmer arm and blade have been shown, it will be understood that, depending on such variables as the size of the clarifier and the quantity and consistency of the float, more than one trough and more than one skimmer arm and blade may be needed. Accordingly, we do not wish to limit ourselves to the exact structural details shown and described herein.

We claim:

1. In a device for removing scum from a basin having a scum trough including a sloping ramp member on its leading side, said ramp member having a leading edge and a trailing edge parallel to one another, said device comprising a skimmer arm adapted to be rotated in said basin, a skimmer blade rotatable with said arm, said ramp member and blade extending inwardly from the periphery of said basin for such a length that said blade approaches said leading edge at an angle and does not conform to the surface of said ramp member, the combination with said blade of connecting means between said arm and said blade permitting said blade to swing about a horizontal axis and to move angularly with respect to said skimmer arm when said blade contacts and moves up said sloping ramp member, said connecting means including a plurality of parallel link members, each link member being rigidly connected to said blade and being pivotally connected with said arm, whereby said blade can adjust itself to the surface of said ramp member as it rises thereon.

2. A scum skimmer for a basin provided with a scum trough having a ramp sloping upwardly to its leading edge, said ramp having a leading edge and a trailing edge parallel to one another, said scum skimmer comprising a skimmer arm rotatable in said basin, and a skimmer blade rotatable with said arm, said ramp and blade extending inwardly from the periphery of said basin for such a length that said blade approaches said leading edge at an angle and does not conform to the surface of said ramp, characterized by connecting means between said arm and said blade permitting said blade to move angularly to, and about the longitudinal axis of, said arm, said connecting means comprising a bar, a single pivot connecting bar to said arm, and a pair of parallel links, each link being pivotally connected with one end to said bar,

and rigidly connected with the other end to said blade, whereby said blade can adjust itself to the surface of said ramp as it rises thereon.

3. In a liquid treating apparatus comprising a tank provided with a scum trough having an open top and including a ramp member leading upwardly to said open top and having an upper edge, extending along a major portion of a radius of said tank, an improved device for moving scum from said tank into said trough, said device comprising a skimmer arm adapted to be rotated in said tank, a bar pivotally connected to one point of said skimmer arm, a pair of parallel links pivotally connected to opposite ends of said bar, said links being provided with stop members that contact said skimmer arm to limit the downward movement of said links, a skimmer blade rigidly connected to said links and extending along a major portion of a radius of said tank, and a squeegee fixed to said blade so as to extend below the lower edge thereof.

4. The apparatus of claim 3, wherein said squeegee is of stiff material and has lateral extensions beyond said blade of flexible material.

5. The apparatus of claim 3, wherein said stop members are adjustable.

6. An improved device for moving scum accumulated in a basin into a scum trough having a sloping ramp member, said device comprising a skimmer arm adapted to be rotated in said basin, a bar, a pivot connecting said bar to said skimmer arm, a pair of parallel links pivotally connected to said bar on opposite sides of, but unequally spaced from, said pivot, stop means limiting the lowermost position of said links, and a skimmer blade rigidly connected to the free ends of said links.

7. A device for moving floatable material from a circular basin into a scum trough fixed to the wall of said basin, said scum trough including a ramp member leading upwardly to the upper edge of said trough and bounded on its sides by the wall of the basin and an extension of an end wall of said trough, said device comprising a central rotatable drive shaft in said basin, said drive shaft being adapted for connection to a prime mover, a skimmer arm rigidly connected to said drive shaft at an elevation above said scum trough, a bar, a pivot connecting said bar to said skimmer arm, a pair of brackets affixed to said bar adjacent each end, a pair of parallel links pivotally supported by said brackets, a skimmer blade rigidly connected to the free ends of said links, and stop means adjustably fixed to said links to limit the lower position of said skimmer blade so that in its lowermost position its lower edge lies in the same horizontal plane as the bottom of said ramp member, said pivot being laterally offset with respect to said brackets.

8. A device according to claim 7, wherein a stiff squeegee is affixed to said blade.
